UNITED STATES PATENT OFFICE.

HILDUR L. CHRISTENSEN, OF ST. PAUL, MINNESOTA.

TOY.

Application filed November 28, 1927. Serial No. 236,175.

My invention relates to a child's toy and the main object is to provide a simple, inexpensive and useful toy embodying a number of features making the device not only a 5 very attractive and interesting toy for small children but also a useful device for storing children's playthings and other articles. These and other objects of my invention will be fully set forth in the following specification, reference being had to the accompanying drawing, in which,—

Fig. 1 is a perspective view of the toy, a portion of one side wall being broken away to expose the interior construction.

Fig. 2 is an enlarged right hand end elevation of an upper corner of the toy showing the top hinge in detail.

Fig. 3 is a top view of Fig. 2.

Fig. 4 is a perspective view of the toy 20 modified, and in reduced scale.

Referring to the drawing by reference numerals my improved toy comprises mainly an upwardly open box or body 5, preferably elongated, and its four lower 25 corners mounted on casters 6. The walls of this box may have any suitable designs, figures or lettering, and in Fig. 1, 7 designates two windows between which is a one piece door 8, normally in vertical position 30 in the plane with its wall but hinged at its lower edge so that it may be swung out and down to rest on the floor, indicated as 8^e in Fig. 1. Thus the door itself serves in its lowered position as a runway for toy automobiles to enter or leave the box when a child uses the device in play as a garage.

Around the upper perimeter of the box, I prefer to secure a reinforcing molding 9, which may have one or two sections 9^s at 40 both sides hinged as at 10 to be swung out horizontally at right angles as to positions indicated 9^s in Fig. 1 to serve as supports for the hinged top 11 which will now be described.

45 The cover or top of this play device comprises preferably two like sections of board 11 normally closing the top and each said section is hinged as at 12 at the opposite corners. Each said board may be a single piece, or two pieces 11^A—11^B (Fig. 2) of which 11^A is the top one. Both sections 11^A and 11^B may be swung out to a horizontal plane away from the edge of the box and rest on the extended arms 9^s thus forming 50 two ledges or shelves one at each side of the open box. Or, as shown in Fig. 2, the arms

are not used but the entire board is swung out and allowed to hang from the hinge (see dotted lines of 11^A and 11^B). In another selective placement of the top, sections 11^B 60 are permitted to lie in their box closing position and sections 11^A are swung out to horizontal plane as 11^A' in Fig. 2, the outer edge of said section bearing inwardly against the outer edge of section 11^B. Thus 65 sections 11^B remain in the box-closing position and sections 11^A are extended sidewise in a common horizontal plane therewith providing a useful table for child's play.

One or more of the surfaces of either sections 11^A—11^B may be prepared with a black surface, preferably that surface of section 11^B which is exposed outwardly when said section is hanging down from hinge 12 and outwardly of the side wall of the box. This 70 colored surface serves as a blackboard on which a child can make chalk marks.

In Fig. 1, 13—14 designates a plain seat arranged transversely across the end of the box opposite the door end, and this seat is 80 made by simply fixing a vertical front board 13 between the side walls of the box, and 14 is a horizontal board with its front edge resting on board 13 and its rear edge hinged as at 15 to the adjacent end wall. Thus 85 board 14 serves not only as a seat but may be raised on its hinges so that toys and other articles may be stored thereunder.

16 in Fig. 1 represents a retaining rope parallel to and spaced upwardly of the front 90 corners of the seat 13—14, being suitably removably fixed to the opposite side walls by eye-screws 17 or equivalent means. This rope is so placed as to be directly in front of a child seated on board 14 and prevents 95 the child from falling forward.

18 is a pulling bar of any suitable type and preferably hinged to the upper part of one end wall so as to hang therefrom when not in use but not touch the floor.

As a useful article, aside from being a useful toy as described it is obvious that this device is readily drawn about on the floor and toys and other articles which are to be stored away temporarily are placed in the 105 box and it is easily rolled to a closet, under a table or any place desired until needed again. It is desirable to have rubber faced rollers on the casters 6 to prevent marking of highly polished floors.

In the modified form of my device shown 110 in Fig. 4 the end walls of the box are sloped

up to a central peak 5^P causing the hinged top section to resemble the sloped roof of a home or garage.

I claim:

5. 1. A toy of the class described comprising a box-like body mounted upon casters supporting the same, a sectional cover hinged at opposite sides of the top of said box and normally closing the top thereof, and a hinged door at one end of the box and adapted to be swung downwardly and outwardly from the box, a seat arranged transversely of and within the box, the top of said seat comprising a hinged flat member, a 10 transversely arranged vertical board on which the free edge of said hinged member rests, a removable strap fixed in the side walls in parallel spaced relation to said seat, said hinged cover adapted to be 15 swung outwardly, and means for supporting said cover sections in a horizontal plane outwardly of the opposite upper edges of the box.
2. The structure specified in claim 1 and 20 a reinforcing strip fixed to the upper perimeter of said box and said strip provided with hinged sections adapted to be swung outwardly horizontally from the box horizontally to support the cover sections.
3. The structure specified in claim 1 in 25 which said cover sections comprise each a pair of identical boards pivotally secured to common hinge members at outer corresponding corners of the box and one board

of each pair adapted to cover a portion of 35 the box and the other board to be swung outwardly and be supported in a common plane with said first mentioned board.

4. The structure specified in claim 1 in which said cover sections comprise each a 40 pair of identical boards pivotally secured to common hinge members at outer corresponding corners of the box and one board of each pair is adapted to cover a portion of the box and the other board to be swung outwardly 45 and be supported in a common plane with said first mentioned board and both boards of each said pair of boards are adapted to be suspended from their hinge members outwardly of the adjacent side of the box. 50

5. The structure specified in claim 1 in which said cover sections comprise each a 55 pair of identical boards pivotally secured to common hinge members at outer corresponding corners of the box and one board of each pair is adapted to cover a portion of the box and the other board to be swung outwardly and be supported in a common plane with said first mentioned board and both boards of each said pair of boards are adapt- 60 ed to be suspended from their hinge members outwardly of the adjacent side of the box, certain predetermined areas of said boards being provided with a slate colored surface 65 for the purpose set forth.

In testimony whereof I affix my signature.

HILDUR L. CHRISTENSEN.
